HIGH FREQUENCY TERMINAL

George Lindley Usselman, Port Jefferson, N. Y.,
assignor to Radio Corporation of America, a
corporation of Delaware

Original application August 14, 1936, Serial No.
96,046. Divided and this application April 21,
1937, Serial No. 138,111

2 Claims. (Cl. 174—142)

This invention relates to an improved compressed neutralizing condenser having a corona shield, and is a division of my copending application Ser. No. 96,046, filed Aug. 14, 1936, now Patent #2,193,500, patented March 12, 1940.

The invention covered by this application relates to the terminal construction of a condenser particularly suited for neutralizing purposes.

One object of my present invention is to provide an improved terminal construction of a gas filled condenser whose capacitive value may be varied. A further object of my present invention is to provide an improved condenser which, though subjected to high voltages, is substantially free of or has a minimum of corona losses. A still further object of this invention is a means to protect the insulation portion of the condenser structure from high voltage forming a metallic creepage path on the surface of the insulator. Other objects, advantages and features of my present invention will be self-apparent as the more detailed description thereof proceeds.

In the accompanying drawing, I have illustrated a cross-sectional view of a neutralizing condenser embodying the various features of my invention.

Referring in detail to the drawing, I have shown a neutralizing condenser provided with an outer electrode or wall 126. The inner electrode structure 128 is adjustable and constructed as described in Hansell et al. Patent #2,192,062, patented Feb. 27, 1940. The upper portion of casing 126 is provided with a cone-like insulator 138 of porcelain, Isolantite, Pyrex or any other suitable material having the necessary and requisite mechanical strength and insulating qualities. The lower end of insulator 138 is provided with a flanged portion 2A over which a metallic ring 3 securely fastens the insulator to casing 126 by the cooperation of collars 4 and 4A and screws 142. To provide a gas-tight seal and also to prevent breakage of the insulator, a lead or rubber gasket 5 is employed between members 138, 4A and 126. Over the outside of member 3, there is provided a hollow ring-like member 140 which acts as the lower portion of a corona shield to prevent an arc-over on the surface of the insulator, due to high voltage; within the central portion of insulator 138, a long hollow stem 6 is located, the lower portion being secured to an inner electrode supporting member 8 which supports the fixed portion of the inner electrode 8. A shoulder portion 10 retains stem 6 against a gasket 11 within the upper portion of insulator 138, the upper portion of stem 6 being

threaded with a fine thread 12 by means of which the adjustable lower portion 17 of the central electrode is raised or lowered within the aperture 1A with the aid of and against the internal fluid pressure and actuated by means of a relatively long adjusting nut 150. The adjustable portion of the central electrode is retained in any desired position by means of the internal fluid pressure always acting upon and forcing the central adjustable electrode portion up against the lower portion of a rod 15. The upper portion of adjustable nut 150 is arranged to retain a small hardened steel ball bearing 14 which actuates rod 15 as it passes through stem 6. Rod 15 terminates in a threaded flanged member 16, upon which is mounted the adjustable lower portion 17 of inner electrode 8.

The outer casing 126 acts as the outer electrode condenser and is arranged to be an integral part of a transmitter circuit assembly by being provided with a spacer 58 which secures the condenser at its proper height on support member 52. The condenser is retained in a fixed position by means of a second support member 53 and a threaded spacing member 54.

To prevent corona creepage along the surface of conical insulator 138, an annular shield or shell 140 which is made to be a snug fit at the base of insulator cone 138, and is provided to shield and completely enclose the round head slotted screws 142 for fastening cone 138 to base 126. As these screw heads frequently give rise to sparking of an arc-over due to their sharp points caused by the use of screw drivers, etc. during the assembly of the condenser terminal, a circular doughnut-shaped corona shield is provided at the upper end or apex of the insulating cone 138 which is in the form of a ring-shaped corona shield, and is supported by means of four metal arms 148. It has been found that by the provision of shields 144 and 140, the condenser may be subjected to voltages twice as great as compared to the voltages at which, without shields, flashover or arcing takes place between points 142 and 148.

While only one modification of this invention has been disclosed, it is to be distinctly understood that condenser terminal construction of this type are capable of other modifications and the invention should not be limited, except as to such limitations as are clearly imposed in the appended claims.

What is claimed is:

1. In high voltage terminal construction, in combination, a casing member, an insulator hav-

ing a shouldered base portion supported by said casing, a ring-like terminal member on the top of said insulator, a clamp ring, a plurality of binding members for clamping the shouldered portion of said insulator to said casing by said clamp ring, a metallic cover in the form of an annular shield having substantially a semi-circular cross-section, said shield located above said clamp ring and arranged to be a snug fit on the outside wall of said insulator for completely enclosing said binding members to prevent sparking or arc-over caused by sharp points thereon, and a hollow metallic ring forming a corona shield located above said cover and secured to an end opposite the shouldered portion of said insulator for reducing the tendency towards surface creepage and arc-over on said insulator.

2. In high voltage terminal construction, in combination, a casing member, an insulator hav-

ing a shouldered base portion supported by said casing, a ring-like terminal member on the top of said insulator, a clamp ring, a plurality of binding members including a plurality of round head slotted screws for clamping the shouldered portion of said insulator to said casing by said clamp ring, a metallic cover in the form of an annular shield having substantially a semi-circular cross-section, said shield located above said clamp ring and arranged to be a snug fit on the outside wall of said insulator for completely enclosing said binding members to prevent sparking or arc-over caused by sharp points thereon, and a hollow metallic ring forming a corona shield located above said cover and secured to an end opposite the shouldered portion of said insulator for reducing the tendency towards surface creepage and arc-over on said insulator.

GEORGE LINDLEY USSELMAN.
